Attorney

UNITED STATES PATENT OFFICE

CLARENCE N. CROCKER, OF EUGENE, OREGON

SPRING WIRE REEL

Application filed September 27, 1930. Serial No. 484,834.

This invention relates to spring wire reels, and an object of the invention is to provide a spring wire reel for holding a coil of spring wire while it is being unwound from the 5 roll.

Another feature of the invention is to provide wavy aperture in the periphery of the reel so that the strand of wire feeds out of the holder without tangling and at the same 10 time prevents casual unwinding of the wire.

Another purpose of the present invention is to make a wire reel to make it convenient for any one such as piano tuners, repairmen, 15 aeroplane factories or other factories and retail stores to handle spring wire without tangling and occupying unnecessary space after a fresh coil of wire has been opened.

Further objects of the invention are to provide a reel of the character referred to that 20 is strong, compact and durable, very simple in its method of assembly, the parts of which may be stamped out of relatively light gauge sheet metal, the parts of which are very easy to assemble and disassemble in placing new 25 rolls of wire in the reel, and that is comparatively inexpensive to manufacture and operate.

With the foregoing and other objects in view, the invention consists of a novel construction, combination and arrangement of parts as will be hereinafter more specifically described and illustrated in the accompanying drawings, wherein is disclosed an embodiment of the invention, but it is to be understood that changes, variations, and modifications may be resorted to without departing from the spirit of the claims hereto appended.

In the drawings wherein like reference 30 characters denote corresponding parts throughout the several views:—

Figure 1 is a side elevation of the reel in accordance with the present invention in the assembled relation.

Fig. 2 is a side view of one of the sections of the reel.

Fig. 3 is a diametric detailed sectional view through the section of the reel in disassembled relation.

Fig. 4 is a detailed diametric sectional

view showing both sections of the reel in the assembled relation.

Fig. 5 is an end view of the reel in the assembled relation.

Fig. 6 is a plan view of the blank of metal 55 from which is formed the spacing bands, and

Fig. 7 is a perspective view of the split locking ring.

In the drawings wherein for the purpose of illustration is shown the preferred embodiment of my invention A indicates generally the reel in the assembled relation which is formed of two disk sections indicated generally at 10, 11 that are detachably coupled together. The disks 10, 11 are formed with 60 a view to fabricating them in a single operation as will be apparent as the description proceeds.

The disks 10, 11 are respectively formed with inwardly directed sleeve hubs 12, 13 70 which in the assembled relation have the confronting edges thereof in abutment to form a bearing for a shaft on which the reel rotates. Both of the walls 14, 15 of the disks slope inwardly from the outer ends of the sleeves 12, 13 to the inner edge of the segmental mounted rims 16, 17 formed on the peripheries of the disks.

It will be apparent that the sleeve hubs, the sloping portions, and the segmental rims, 80 provide for forming the disks 10, 11 out of a single blank of relatively thin metal such as sheet steel. The confronting outer edges of the segmental rims 16, 17 are cut to a waving configuration as at 18, 19 so that when the 85 disk sections 10, 11 are assembled and properly spaced as will appear, there is a continuous wavy slot 21 formed in the outer periphery of the reel as will appear in Fig. 5 of the drawings. The rims 16, 17 each have a 90 series of circular openings 22, 23 in their side walls to permit the cutting of the band wire that holds the roll of wire together as it is shipped from the factory. Each one of the 95 series of openings on each rim 16, 17 are in alinement with each other.

In the sloping portion 15 of the section 11 are formed an annular series of spaced slots 24 through which extend the spaced locking ears 25 formed on one edge of the spacing 100

band 26. When applied, these ears 25 are bent into overlapping relation on the outer face of the sloping portion 15 and riveted or otherwise secured, which construction holds the facing band edgewise between the disk sections 10, 11.

On the sloping portion 14 of the disk 10 are an annular series of spaced slots 27 which in the stamping operation are made to register with the narrow slots 25 in disk section 11. The width of the series of slots 27 should accommodate the insertion and withdrawal of the spaced locking fingers 28 formed on the edge of the locking band 26 opposed from the ears 25.

From an inspection of Fig. 6 of the drawings it will be apparent that the locking band 26 may be stamped from a single length of metal *a* whereupon the spaced ears 25 and the locking fingers 28 may be formed in the stamping operation when the blank is cut. When the locking ears 25 are threaded through the series of slots 24 and bent over the band 26 will be supported in a circle edgewise between the two sections 10, 11. The ears 28 may be bent at an angle to the plane of the band so as to form hooks when projected through slots 27 to the outer face of the sloping portion 14 of this disk 10 as will be clearly understood by referring to Figs. 4 and 1 of the drawings.

When the disks are assembled, the locking fingers 28 will form an annular series of fingers 29 to receive the split ring 30 that is forced under the projecting locking fingers or cleats 28 for locking the two disk sections together. The opposed edges of the bands will hold the two disk sections spaced apart when in the locked relation so that the slot 21 will be formed between the confronting wavy edges of the segmental portions 16, 17 of the disks.

In the assembled relation the two segmental ends 16, 17 will form a circular pocket 31 that contains the coil of spring wire 24 that is used and a new coil is to be placed in the pocket 31, the ends of the split ring are flexed inwardly and removed from the projecting locking fingers 28. When this is accomplished, the disk sections 10, 11 are moved apart as shown in Fig. 3 of the drawings, whereupon a new coil of spring wire 24 containing the tying bands is inserted within the rims 16, 17. Then the disk sections are locked together. Thereafter the bands that hold the coils may be cut through the openings 22, 23 in the peripheral walls of the respective rims 16, 17.

The present embodiment of the invention has been disclosed in considerable detail merely for the purpose of exemplification since in actual practice it attains the features of advantage enumerated as desirable in the statement of the invention and the above description.

It is to be understood that by describing in detail herein any particular form, structure, or arrangement, it is not intended to limit the invention beyond the terms of the several claims or the requirements of the prior art.

Having thus described my invention what I claim as new is:—

1. A wire reel comprising a body having a chamber about its perimeter adapted to receive a coil of wire therein, and said body having a wavy perimetral slot therein in connection with said chamber.

2. A wire reel comprising a body having a chamber about its perimeter adapted to receive a coil of wire therein, said body having a wavy perimetral slot therein in connection with said chamber, and means for separating the walls of the chamber to allow the replacement of a coil of wire therein.

3. A wire reel comprising a pair of disks, having segmental shaped rims, a spacing band locked to one of the disks, said spacing band having locking fingers at one edge, the other disk formed with a series of slots through which the locking fingers extend in the assembled relation, a split ring insertible under the locking fingers for holding the disks together, and the outer edges of the segmental rims of the disks being wavy and spaced apart to form a wavy peripheral slot in the rim of the reel in the assembled relation.

4. A reel of the class described comprising a circular body having an annular chamber at its periphery, said chamber being of circular shape in cross section and said body having a wavy slot in its outer circumference and openings in its sides, said slot and openings being in communication with the chamber.

In testimony whereof I affix my signature.

CLARENCE N. CROCKER.
